UNITED STATES PATENT OFFICE.

HAROLD E. MCCREBBY, OF APOLLO, PENNSYLVANIA, ASSIGNOR TO PITTSBURGH STEEL DRUM COMPANY, OF PITTSBURGH, PENNSYLVANIA, A CORPORATION OF DELAWARE

METAL SHIPPING DRUM.

Application filed January 14, 1928. Serial No. 246,884.

This invention relates to metal shipping drums.

It is the present practice to provide metal shipping drums with beads at the end portions thereof about which similarly shaped flanges formed on the heads are rolled to form the completed sealed drum. In some instances, one of the drum heads is provided with a relatively small central opening covered by a closure cap through which access may be had to the interior of the drum to remove the contents therefrom. The use of the closure caps referred to is impracticable when the drums are employed for shipping liquids owing to the difficulty in effectually sealing the cap, and under such circumstances, it is necessary to remove one of the heads which can be done only by detaching the rolled flange thereof, thus mutilating the head and rendering it unfit for further use. It also has been found difficult to seal the end portions of the body of the drum owing to the fact that the lips formed at the ends of the sheet comprising the body of the drum to form an interlocking seam, cannot be extended throughout the height of the sheet owing to the provision of the beads previously referred to. When rolling the flanges of the head beneath the bead, the portions of the flange lying adjacent the interlocking seam of the body do not cooperate therewith in such a manner as to form a leak-proof joint, and it is for this reason that it has been found difficult to provide a metal shipping drum which is adapted for the shipment of liquids.

An important object of the present invention is to provide novel means for sealing the end portions of the interlocking seams whereby a liquid tight drum is provided when the heads of the drum are attached thereto.

A further object is to provide a drum of the character referred to wherein compressible means is provided for bridging across the drum at the ends of the interlocking seam thereof to effect a leak-proof joint.

A further object is to provide novel means for effecting compression of the compressible sealing member.

A further object is to provide a novel form

of head for a drum which may be detached without mutilation thereof to permit its use for covering the drum after the contents thereof have been only partially removed.

A further object is to provide a novel drum head of the character referred to, which, after the drum has been opened, is adapted to be employed as a cover for the drum and to be frictionally retained in closed position.

A further object is to provide a drum of the character referred to having a bead at least one end thereof, a head having flange portions adapted to frictionally engage the bead to retain the head in position, and to provide means for securing the head to the drum to permit its use in the shipment of material.

Other objects and advantages of the invention will become apparent during the course of the following description.

In the drawings I have shown several embodiments of the invention. In this showing,

Figure 1 is a side elevation of the drum, Figure 2 is a detail fragmentary sectional perspective view of one end portion of the drum, parts being shown detached;

Figure 3 is a fragmentary detail section on line 3—3 of Figure 1 showing the parts in assembled position,

Figure 4 is a fragmentary perspective view of a portion of one end of the drum showing the seam thereof and associated elements detached,

Figure 5 is a fragmentary sectional view taken through the seam at one end of a drum showing the modified form of the invention with the elements partially assembled, and,

Figure 6 is a view similar to Figure 5 showing the complete assembly of the elements.

Referring to the drawings, the numeral 10 designates the body of the drum which is preferably formed of sheet metal of the proper gauge according to the use to which the drum is to be put. Each end of the sheet of metal forming the body of the drum is provided with suitably shaped extensions 11 which are adapted to be interlocked to form an ordinary interlocking seam 12. The end portions of the body are rolled as at 13 to form beads of the usual type, and as shown in Figure 3,

the beads obviously terminate at suitable points to permit the seam elements to be assembled. It will be apparent that the seam members cannot be extended throughout the 5 height of the sheet forming the body of the drum, owing to the presence of the beads 13. The structure is such therefore that it is extremely difficult to provide a suitable head for the drum which will prevent leakage of liquids 10 between the ends of the beads 13, which lie substantially in contact with each other when the drum is assembled.

Referring to Figures 2, 3 and 4, the numeral 14 indicates a sealing clip as a whole 15 which is substantially of an inverted J-shape, and comprises an outer metallic member 15 and an inner compressible member 16 preferably formed of rubber. The clip 14 is adapted to be placed in position as indicated in 20 Figure 2.

Referring to Figures 2 and 3, the numeral 17 designates one of the heads of the drum which is provided at its periphery with an annular flange 18 curved in cross-section to 25 conform to the curvature of the bead 13 and clip 14. It will be apparent that the thicknesses of the elements comprising the clip are relatively exaggerated in the drawings, the clip being sufficiently thin in the practical embodiment of the invention to permit the flange 30 18 readily to be placed in position over the end of the drum. The bead 13 is preferably substantially circular in cross-section, and it will be apparent from Figures 2 and 3 that 35 the free edge of the flange 18, when in assembled position, extends slightly below the center line of the bead 13, as indicated at 19, for a purpose to be described.

Referring to Figures 2 and 3, the numeral 40 20 designates a clamping band adapted for positively securing each head in position. The band 20 is curved in cross-section throughout a considerable portion of its width, the skirt portion 21 of the band being substantially cylindrical before assembly 45 of the elements, as shown in Figure 2.

A somewhat modified form of the invention is shown in Figures 5 and 6, wherein the clamping band 20 is omitted. In this form 50 of the invention, the drum is provided with a head 22 similar to the head 17 previously described, except that it is provided with a flange 23 of materially greater width than the flange 18. The flange 23 is normally provided with a substantially cylindrical skirt portion 24.

The operation of the device is as follows: The body portion of the drum is assembled 60 in the usual manner by bringing together the seam elements 11 and rolling them to form the seam 12. The seam elements may be welded together, if desired, to assure the provision of a leak-proof joint. When the body of the drum is thus assembled, it will 65 be apparent that the end portions of the

bead 13 will lie adjacent each other. The clip 14 is then placed in position, the wider portion of the clip being arranged externally of the drum, as shown in Figure 2. The clip bridges across the ends of the beads 13, as 70

will be apparent, and after it has been so positioned, the head 17 is placed in position with the flange 18 arranged over the bead 13 and clip 14. The clamping band 20 is then slipped over the end of the drum, 75

after which the skirt portions of the clip 14, flange 18 and band 20 are rolled inwardly as indicated in Figure 3. The outer edges of the metallic member 15 and compressible member 16 preferably coincide before the 80

rolling action takes place, as shown in Figures 2 and 4, and it will be apparent that when the rolling action is performed, the compressible member tends to elongate with respect to the metallic member of the clip, 85

owing to the difference in the cross sectional circumferences of these elements when so rolled. Thus it will be apparent that a piling up of the compressible material occurs. This action causes the compressible element 90

not only to surround the bead, but to overhang the edge of the member 15 and lie against the body of the drum between the bead 13 and the upper extremities of the seam elements 11. The rolled edge of the element 95

15 then retains the member 16 under compression to effect a leak-proof joint at the ends of the body adjacent the seam. The skirt of the clamping band is rolled around the bead 13 as shown in Figure 3, and effectually secures the head 17 to the body of the 100 drum. The structure illustrated in Figures 2, 3 and 4 may be employed at both ends of the drum; or it may be employed at one end with the modified form of the invention arranged at the opposite end. The operation of the modified form of the device will be referred to later.

When the drum reaches the consumer, and it is desired to wholly or partially remove the contents of the drum, a screw driver or other similar implement is inserted beneath one edge of the clamping band 20 to permit the implement to slide therebeneath. Thus it will be apparent that the clamping band 110 readily may be ripped off, after which it is discarded. As previously stated, the edge 19 of the flange 18 extends a slight distance below the center of the bead 13 and thus will be frictionally retained in position, but the head readily may be removed merely by tapping upwardly against the edge 19. If the contents of the drum are only partially removed, the remaining portions of the contents may be protected by placing the head 115 upon the drum. The outer edge portion of the flange 18 will snap over the bead 13, thus retaining the head in position against accidental dislodgment.

So far as the sealing means is concerned, 120

the form of the invention illustrated in Figures 5 and 6, is identical with that previously described. In the modified form, however, the clamping band is eliminated and the bead 23 is widened whereby the skirt portion thereof when rolled beneath the bead 13, will effectually retain the head in position. The removal of the head may be effected by inserting a screw driver or similar implement beneath the edge thereof, and this action obviously bends and distorts the flange of the head. This form of the invention is employed where the contents of the drums are entirely removed, thus rendering it unnecessary to utilize the head as means for protecting a portion of the contents of the drum. The sealing clip 14 operates in the manner previously described, and thus it will be apparent that both forms of the drum are adapted for the shipment of liquids since leakage of the latter is effectually prevented.

It is to be understood that the forms of the invention herewith shown and described are to be taken as preferred examples of the same and that various changes in the shape, size and arrangement of parts may be resorted to without departing from the spirit of the invention or the scope of the subjoined claims.

I claim:

1. A shipping drum comprising a substantially cylindrical body having a bead extending around one end thereof, the ends of the sheet forming said body being joined by a seam extending to a point adjacent said bead, means for sealing the end of said body between the ends of said bead against leakage, and a head closing the end of said body.

2. A shipping drum comprising a substantially cylindrical body having a bead extending around one end thereof, the ends of the sheet forming said body being joined by a seam extending to a point adjacent said bead, a clip bridging across the end portions of said bead and extending therebeneath, and a head closing the end of said body.

3. A shipping drum comprising a substantially cylindrical body having a bead extending around one end thereof, the ends of the sheet forming said body being joined by a seam extending to a point adjacent said bead, a clip bridging across the end portions of and extending around said bead, said clip including an inner compressible member, and a head closing the end of said body.

4. A shipping drum comprising a substantially cylindrical body having a bead extending around one end thereof, the ends of the sheet forming said body being joined by a seam extending to a point adjacent said bead, a clip bridging across the end portions of and extending around said bead, said clip including an inner compressible member, and a head closing the end of said body, said head

being provided with a peripheral flange extending over and engaging said bead and said clip.

5. A shipping drum comprising a substantially cylindrical body having a bead extending around one end thereof, the ends of the sheet forming said body being joined by a seam extending to a point adjacent said bead, a substantially J-shaped clip bridging across the end portions of said bead and having the longer end thereof rolled beneath said bead, said clip including an inner compressible member, and a head closing the end of said body.

6. A shipping drum comprising a substantially cylindrical body having a bead extending around one end thereof, the ends of the sheet forming said body being joined by a seam extending to a point adjacent said bead, a clip bridging across the end portions of said bead and extending therebeneath, a head closing the end of said body, said head including a peripheral flange extending over said bead, and a clamping ring surrounding the upper end of said body and extending over said flange and beneath said bead.

7. A shipping drum comprising a substantially cylindrical body having a bead extending around one end thereof, the ends of the sheet forming said body being joined by a seam extending to a point adjacent said bead, a clip including an outer metallic member and an inner compressible member, said clip bridging across the end portions of said bead and extending therebeneath with the compressible member thereof contacting with the bead and with the side of said body, and a head closing the end of said body.

8. A shipping drum comprising a substantially cylindrical body having a bead substantially circular in cross-section extending around one end thereof, and a head closing the end of said body, said head having a peripheral flange curved to conform to the curvature of said bead and extending thereover, the edge of said flange extending inwardly slightly beyond the center of curvature of said bead.

9. A shipping drum comprising a substantially cylindrical body having a bead substantially circular in cross-section extending around one end thereof, a head closing the end of said body, said head having a peripheral flange curved to conform to the curvature of said bead and extending thereover, the edge of said flange extending inwardly slightly beyond the center of curvature of said bead, and an annular clamping ring for securing said head to said body, said ring extending over said flange and beneath said bead.

10. A shipping drum comprising a substantially cylindrical body having a bead substantially circular in cross-section extending around one end thereof, a clip including an

inner compressible member bridging across the end portions of said bead and extending therebeneath, the end portion of said member contacting with the side of said body between 5 said bead and said seam, a head closing the end of said body, said head having a peripheral flange conforming to the cross-sectional curvature of said bead and extending there-

over, the edge of said flange extending inwardly slightly beyond the center of curvature of said bead, and an annular clamping ring for securing said head to said body, said ring extending over said flange and beneath said bead. ¹⁰

In testimony whereof I affix my signature.
HAROLD E. McCRARY.
